UNITED STATES PATENT OFFICE.

SYLVESTER P. FROST, OF DALLAS, TEXAS.

SCRAPER.

Application filed October 28, 1926. Serial No. 144,750.

The invention relates to improvements in scrapers, such as those which may be conveniently used when washing dishes, pots, pans and other utensils, when painting objects, requiring slight scraping at numerous points, when cleaning windows upon which dry putty and paint spots exist, etc.

It is one object of the invention to provide a scraper of novel form which is carried by a ring, said ring being adapted to surround the user's thumb, the scraping blade being provided with a thumb-receiving channel and having scraping edges which project laterally from said channel.

Another object is to make unique provision for forming the scraping blade and ring from a single metal blank.

A still further aim is to provide a unique form of expansible and contractible ring including a projecting portion which may be held by the forefinger, when comparatively heavy work is to be done.

With the foregoing in view, the invention resides in the novel subject matter herein-after described and claimed, the description being supplemented by the accompanying drawing.

Fig. 1 is a perspective view of a scraper constructed in accordance with the invention.

Fig. 2 is a longitudinal sectional view as indicated by line 2—2 of Fig. 1.

Fig. 3 is a transverse section on line 3—3 of Fig. 2.

Fig. 4 is a plan view of the metal blank from which the device is formed.

In the drawing above briefly described, the numeral 5 designates a ring to surround the user's thumb and 6 denotes a scraping blade secured to and projecting forwardly from said ring. This blade is elongated in a forward to rearward direction and is formed with a longitudinal thumb-receiving channel 7 along its central portion, while the longitudinal edge portions 8 of said blade project laterally beyond said channel to provide scrapers. These edges and the front end of the blade 6 are all preferably curved convexedly.

In the preferred manner of constructing the device, I make use of the metal blank shaped as shown in Fig. 4. The shank portion S of this blank is bent to form the blade 6 and the head portion H is curved to provide the ring 5. The edges of this ring-forming head are inwardly folded as at 9

and 9^a and as the inner end of the blade-forming shank S is integral with the inwardly folded edge 9, it is again folded outwardly as seen in Fig. 3. A strong integral connection is thus provided between the blade and ring and the turned edges of the latter will be comfortable to the user.

The end portions 11 and 12 of the head H are outwardly turned, the end 12 being longer than the end 11 and bent into a loop, overlapping the shorter end. By this provision, the ring 5 may readily expand or contract according to the size of the user's thumb and if desired, the loop 13 may be either contracted or enlarged by bending, as occasion may demand.

In using the device, it is turned to such a position as to permit it to slip easily onto the thumb, in which connection, attention is directed to the fact that the ring 5 is of slightly ovate form, and the normal thumb is more or less elliptical or oval in cross section. The ring having been placed upon the thumb in this manner, it may be turned to position the blade 6 in the most advantageous manner. There is no danger of the ring dropping from the thumb and it insures that the blade 6 shall be in readiness for use whenever such use will be of advantage, regardless of the character of work being done. When doing exceptionally heavy work, the forefinger may be engaged around the loop 12—13—14, so that such finger may be used to brace the thumb, thus assisting in rigidly holding the ring and the blade.

As excellent results are obtainable from the details disclosed, they are preferably followed. However, within the scope of the invention as claimed, variations may be made.

I claim:

1. A device of the class described comprising a ring having its front edge portion rearwardly folded upon itself, and a blade having its rear end integral with the free edge of said folded edge portion and extending across the latter.

2. In a device of the class described, a ring formed from a single strip of metal having its end portions outwardly turned, one of said ends being longer than the other end and bent to form a loop and having its end overlapping the shorter end.

3. A scraper comprising a blade and a ring carrying the same, said ring being adapted to surround the user's thumb and having an outward projection on its periph-

ery around which to engage the forefinger to brace the thumb and assist in holding the ring and blade rigidly.

4. A scraper formed from a single metal blank and comprising a head in the form of a thumb receiving ring, the front and rear edges of said head being inwardly fold-

ed upon themselves and a blade extending across the inner face of the inwardly folded front edge portion. 10

In testimony whereof I have hereunto affixed my signature.

SYLVESTER P. FROST.
